[57] CLAIM

I claim the ornamental design for quartz fin heat retaining tube, as shown.

DESCRIPTION

FIG. 1 a perspective view of a quartz fin heat retaining tube.
FIG. 2 is a top plan view thereof.

FIG. 3 a front elevational view thereof, the rear elevational view being a mirror image of the front view.

FIG. 4 a left side view thereof.

FIG. 5 a right side view thereof.

FIG. 6 a bottom plan view thereof.

FIG. 7 a cross sectional view thereof taken along line 7—7 in FIG. 2; and,

FIG. 8 a cross sectional view thereof taken along line 8—8 in FIG. 3.
